UNITED STATES PATENT OFFICE.

WILLIAM H. ROSE, OF JERSEY CITY, NEW JERSEY.

VENTILATING DEVICE.

Application filed December 17, 1926. Serial No. 155,444.

My invention relates to ventilating devices and refers particularly to devices of this character adapted to deflect air admitted below a partially open window in an upwardly direction.

Devices of this character are positioned angularly with respect to a window and maintained in position by supporting members attached to, or carried by, the opposite sides of a window frame.

My device contains a number of valuable properties not contained in the present known devices of this character and its novelty and usefulness will be evident upon a consideration of this specification and its accompanying drawings.

In the accompanying drawings illustrating one form of the device of my invention, similar parts are indicated by similar numerals.

20 Figure 1 is a front view of one form of my device installed within a window frame.

Figure 2 is a cross-section through the line 2—2 of Figure 1.

25 Figure 3 is a perspective view of a portion of my device partly broken away for purposes of clearness of description.

Figure 4 is an enlarged vertical cross-section showing a means employed for fixing the light-transmitting element.

30 The particular form of the device of my invention shown in the accompanying drawings comprises two pieces, or sheets, of heavy cardboard 10 and 11 of longitudinal shape and of such length as to extend between two opposite window frame sides as explained later. Each cardboard sheet has an elongated opening 12, 12, the two openings being in alignment with each other.

35 Positioned between the two cardboard sides 10 and 11 and extending across the aligned openings 12, 12 is a sheet of the material known commercially as cel-o-glass 13 which is a light-weight, flexible, waterproof material, made by coating wire mesh with a clear, transparent or translucent substance which will not rub off, dry up or become brittle. The cel-o-glass sheet is retained in fixed position by means of a plurality of wire staples, or fasteners 14, 14 which extend through the two cardboard sides and the cel-o-glass and are turned over and clinched.

40 A further plurality of similar fasteners 15, 15 are positioned, nearer the edges of the 55 cardboard sides, these last mentioned fasten-

ers not passing through the cel-o-glass in the particular form of my device shown in the accompanying drawings.

The operation of my device is as follows:— A triangularly shaped piece of material, as wood, metal, etc., 16 is fastened to opposite sides of a window frame 17, the outer edge of the support 16 being positioned angularly to the window frame and having a channel 18 therein for the reception of my device. 60 My device is of such shape and size that it can be readily passed downwardly into the two channels 18, 18 of the support 16 and thus be held in angular position with respect to a window 19, thus causing the inflow 70 of air through the partially raised window to be directed upwardly.

It is evident that light admitting materials other than cel-o-glass may be employed, but I prefer this particular material because of its valuable properties as aforementioned, in addition to which it admits the passage of the beta-violet rays of the sun, the beneficial results of which can not be obtained by some of the other light transmitting materials.

The device may be painted and waterproofed, if desired.

Among the valuable properties of my device not possessed by any other one device 85 for the indicated purpose, I may mention, its non-rattling due to the contact of cardboard with metallic supports; the absence of breakage incident to glass; the ease with which it can be produced, not requiring 90 putty rabbeting; its extreme cheapness; its lightness; the ease with which it may be cut by the user to the desired width to accommodate it to a particular window and its durability, and in addition, the property of 95 allowing of the passage of the ultra violet rays when cel-o-glass is employed as the light admitting material.

By "cardboard" I mean and include fibrous and similar materials of a physical 100 character allowing of the insertion therethrough of means capable of retaining the light admitting member.

It is to be noted, therefore, that my ventilating device possesses qualities and properties not possessed by any of the previously employed ventilators and that these new and novel attributes are useful and valuable.

I do not limit myself to the particular size, shape, number, arrangement or mate- 110

rial of parts as shown and described, as these are given simply as a means of clearly describing my device.

What I claim is:—

- 5 1. In a ventilating device capable of angular position with respect to a window, two triangular side pieces each having a groove therein; a front member capable of placement within the grooves of the side pieces.
- 10 10 the front member comprising two sheets of cardboard having aligned openings therein; a sheet of cell-o-glass between the two sheets of cardboard and extending across the openings and fastening means extending through
- 15 15 the cell-o-glass and the two sheets of cardboard.

2. In a ventilating device capable of angular position with respect to a window, two triangular side pieces each having a groove therein; a front member capable of placement within the grooves of the side pieces, the front member comprising two sheets of cardboard having aligned openings therein; a sheet of cell-o-glass between the two sheets of cardboard and extending across the openings and stitched fastening means extending through the cell-o-glass and the two sheets of cardboard.

Signed at New York city in the county of New York and State of New York this 15th day of December, 1926.

WILLIAM H. ROSE.
